Victor J. Evans ATTORNEY

UNITED STATES PATENT OFFICE.

JOSHUA A. YOUNGS, OF BALDWIN HARBOR, NEW YORK.

EJECTOR FOR CIGARETTE AND CIGAR HOLDERS.

1,314,456.

Specification of Letters Patent. Patented Aug. 26, 1919.

Application filed June 21, 1918. Serial No. 241,235.

To all whom it may concern:

Be it known that I, JOSHUA A. YOUNGS, a citizen of the United States, residing at Baldwin Harbor, Long Island, in the county 5 of Nassau and State of New York, have invented new and useful Improvements in Ejectors for Cigarette and Cigar Holders, of which the following is a specification.

This invention relates to cigarette and 10 cigar holders and particularly to ejecting devices for expeditiously effecting removal of the cigarette or cigar as the case may be, from the holder without the necessity of having to grasp the same between the fingers 15 of the hand.

The objects of the invention reside in the provision of a device of this class which is readily applicable to stock holders without requiring expensive alterations in the construction thereof; one which will not distract from the beauty and ornamentation of the holder; one which will be of a relatively compact construction wherein it is capable of lying in flat contact with the holder 25 so as to not form an obstruction to the removal of the holder from the pocket of the user; one wherein the effective ejecting end of the device is designed to always present itself for active engagement with the end 30 of the cigarette on the insertion of the latter in the holder, and one which will be positive of action at all times.

With the above and other objects in view which will appear as the nature of the invention is better understood, the same consists in the improved construction and novel arrangements of parts which will hereinafter be fully described and particularly pointed out in the claim.

40 In the accompanying drawing has been illustrated, a single and preferred form of the invention, it being however, understood that no limitations are necessarily made to the precise structural details therein exhibited, but that changes, alterations and modifications within the scope of the claim may be resorted to when desired.

Figure 1 is a perspective view of a cigarette holder showing the application of the 50 invention thereto.

Fig. 2 is a longitudinal section through a portion of the holder showing the ejector in a normal position in full lines and in a distended position in dotted lines.

Fig. 3 is a transverse section taken on the line 3—3 of Fig. 2.

Fig. 4 is a perspective view of the ejector.

In carrying the invention into practice, use is made of a cigar or cigarette holder such as the one conventionally illustrated at 5 herein. At the outer end of the holder is a guide band 6 in which diametrically disposed grooves 7—7 are formed. This band is cemented or otherwise suitably secured to the holder and it is designed to form a stop 65 for a purpose to be hereinafter described.

The ejector proper consists of a band 8 which is slidable upon the holder 5 and with relation to the stop band 6. Extending from the band 8 are arms 9—9 which 70 are provided with off-set ends 10—10 having extensions 11 formed thereon and arranged parallel with the arms 9—9 as shown in Figs. 2 and 4 of the drawing. The off sets 10—10 extend across the walls of the 75 holder 5 and the branches 11 are arranged in close sliding contact with the inner walls of the holder 5. The branches 11 extend through that portion of the length of the holder which is necessary to permit of an 80 effective purchase of the holder with the cigarette when the latter is applied as shown in dotted lines in Fig. 2. The branches 11 of the arms 9—9 are provided with effective 85 ejecting lugs 12 which extend toward the center of the holder and which are therefore arranged in the direct path of insertion of the cigarette. In this manner, the lugs are adapted to rest against the end of the cigarette when the latter is applied. 90

Movement of the ejector in one direction is limited by the off-sets 10—10 coming in contact with the outer end of the holder 5. Movement in an opposite direction of the ejector is limited by the band 8 contacting 95 with the fixed band 6. When it is desired to eject a cigarette from the holder, the band 8 is grasped between the fingers of the hand and by moving the same in a forward direction, the lugs 12 are forcibly brought 100

against the ends of the cigarette and the latter effectively and entirely released from the holder.

What is claimed as new is:—

- 5 A cigarette holder having a band around its outer end, said band having diametrically arranged slots in its inner periphery, a second band slidably engaging the outer part of the holder and normally spaced from the 10 first band, U-shaped members carried by said

sliding band and normally embracing the walls of the cigarette receiving opening and the outer legs of said member engaging the slots in the other band, and the inner legs engaging the inner walls of the holder and 15 inwardly projecting lugs on the ends of said inner legs and extending at right angles thereto.

In testimony whereof I affix my signature.
JOSHUA A. YOUNGS.
